SARGENT & CO., OF SAME PLACE.

Design No. 3,693, dated October 5, 1869.

DESIGN FOR A SHUTTER-HOOK.

The Schedule referred to in these Letters Patent and making part of the same.

To all whom it may concern:

Be it known that I, F. W. BROCKSIEPER, of New Haven, in the county of New Haven, and State of Connecticut, have invented a new Design for Shutter-Hook; and I do hereby declare the following, when taken in connection with the accompanying drawings, and the letters of reference marked thereon, to be a full, clear, and exact description of the same, and which said drawings constitute part of this specification, and in—

This invention relates to a design for hook used for securing shutters or blinds on the inside; and consists in the peculiar configuration of the plates, hook, and stud, all as fully shown in the accompanying drawings.

I claim, as my invention—

The design for shutter-hook, as shown.

F. W. BROCKSIEPER.
